UNITED STATES PATENT OFFICE.

WILLIAM W. ROBERTSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-REPLENISHING MECHANISM FOR TERRY LOOMS.

Application filed April 5, 1922. Serial No. 549,747.

To all whom it may concern:

Be it known that I, WILLIAM W. ROBERTSON, a subject of the King of Great Britain, residing at Worcester, in the county of 5 Worcester and State of Massachusetts, have invented a new and useful Weft-Replenishing Mechanism for Terry Looms, of which the following is a specification.

This invention relates to the application 10 of weft replenishing mechanism to a so-called "Terry" loom in which Turkish toweling or other uncut pile fabrics are woven.

More particularly, it relates to that type 15 of Terry loom in which the lay and reed as a unit have two distinct ranges of movement, in contrast to Terry looms of the movable reed type.

It is the object of my invention to provide 20 weft replenishing mechanism so positioned that it will cooperate with the lay when the latter is oscillated in one range of movement only, preferably the rearward range.

A further object of my invention is to 25 provide shuttle driving mechanism so arranged and timed that the shuttle will be housed on the magazine end of the lay only when the lay is moving in its operative range as considered with reference to the 30 weft replenishing mechanism. My invention therefore pertains particularly to Terry looms in which the full cycle of changes in the ranges of movement occupy an even number of picks or beats of the lay, 35 so that the shuttle will always occupy the same shuttle-box at the same point in the cycle of operations of the loom.

My invention further relates to arrangements and combinations of parts which will 40 be hereinafter described and more particularly pointed out in the appended claims.

A preferred form of my invention is shown in the drawings in which—

Fig. 1 is a side elevation of a Terry loom 45 embodying my improvements, and

Fig. 2 is a detail side elevation showing the parts in a different relative position.

Referring to the drawings, I have indicated a loom frame 10, and a lay 11 mounted 50 to oscillate on swords 12 about a rock shaft (not shown) near the bottom of the frame 10. The lay is actuated through connecting rods 13 from a crank shaft 14 mounted

in movable bearings 15. The bearings 15 are of cylindrical form and may be moved 55 angularly in journal boxes 16.

For this purpose, arms 17 on the bearings 15 are connected by links 18 to arms 19 on a cross shaft 20. The shaft 20 is supported in bearings 21 in the lower rear part 60 of the frame 10 and is provided with an operating arm 22 connected by a link 23 to a lever 24 pivoted at 25 on the loom frame 10.

A spring 26 moves the lever 24 yieldingly 65 upward, shifting the bearing boxes 15 to their rearward position, as shown in Fig. 2, and the lever 24 is moved positively in the opposite or downward direction when engaged by a roll 27 on an arm 28 fixed 70 to the shaft 29 which drives the pick cams 30.

The shaft 29 is gear-driven from a shaft 31 and, as shown in the drawing, is arranged to make one revolution for every 75 two revolutions of the shaft 31. The shaft 31 is the usual cam or bottom shaft, driven by 2-to-1 gear connections (not shown) from the usual crank shaft 14. The shaft 29 thus makes one revolution to each four 80 revolutions of the crank shaft 14 and to each four beats of the lay. This exact ratio is not essential to my invention, but it is necessary that the crank shaft boxes 15 be shifted in the same direction only at intervals of an even number of picks. 85

The usual picker sticks 32 are actuated through pick shafts 33 by the pick cams 30 which cooperate with cam rolls 34 mounted 90 on the pick shafts.

The parts thus far described are or may be of the usual construction and in themselves form no part of my present invention.

The weft replenishing mechanism shown in the drawings comprises a magazine 40 95 of the stationary type supported in fixed position on the loom frame and having the usual operating mechanism for a magazine of this type, including a transerrer 41 by which a fresh weft carrier is advanced to 100 the shuttle to replace a substantially exhausted weft carrier therein.

Weft detecting mechanism 42, also of a usual type, is indicated in the drawings and both the weft replenishing mechanism 105 and the detecting mechanism are positioned

to cooperate with the lay when the latter is moving in one only of its ranges of movement, preferably the rearward range.

As the weft detecting and replenishing mechanism is not in operative relation with the lay when the latter is positioned in its forward range of movement, I have so constructed and related the several parts of the loom that the picking mechanism will always house the shuttle S at the end of the lay remote from the magazine as the lay is advancing in its forward range of movement.

A single shuttle box is provided at the magazine side of the loom, the invention not being applicable to a "pick and pick" loom. Drop boxes of the usual type may be used at the opposite side of the loom.

The loom being started with the shuttle at the drop box side on the forward range of the lay and this range being operative only after an even number of picks, it follows that the shuttle is presented at the magazine end of the lay only when the lay is travelling in its rearward range of movement and when the lay is consequently in operative relation with the magazine and weft detecting mechanism.

While herein shown in connection with mechanism for weaving a four pick Terry fabric, my invention is equally applicable to any Terry weave involving a cycle of an even number of picks.

It should be further understood that the magazine and detecting mechanism shown in the drawings are illustrative only, as the utility of my invention is not limited to a particular form or type of magazine or detector.

Having thus described my invention and the advantages thereof, I do not wish to be limited to the specific details herein disclosed otherwise than as set forth in the claims, but what I claim is:—

1. In a loom, a lay having forward and rearward ranges of movement, means to oscillate said lay, means to shift the range of movement thereof forward or rearward

at predetermined intervals, a shuttle on said lay, weft replenishing mechanism positioned to cooperate with said shuttle in one range of movement only of said lay, and shuttle driving mechanism timed to house the shuttle on the magazine end of the lay only when said lay is shifted to operative relation with said weft replenishing mechanism. 50 55

2. In a loom, a lay having forward and rearward ranges of movement, means to oscillate said lay, means to shift the range of movement thereof forward or rearward in a cycle comprising an even number of beats of the lay, a shuttle on said lay, a weft replenishing mechanism positioned to cooperate with said shuttle when the lay is moving in one range of movement only thereof, and shuttle driving mechanism timed to house the shuttle on the end of the lay remote from the magazine whenever the lay beats up in inoperative relation with said weft replenishing mechanism. 60 65 70

3. In a loom, a lay having two ranges of movement, means to oscillate said lay, means to periodically change the range of movement thereof, a weft replenishing mechanism positioned to cooperate with said lay in its rearward range only, a shuttle, and shuttle driving mechanism effective to present the shuttle to the magazine end 75 80 of the lay only when said lay is traveling in its rearward range of movement.

4. In a loom, a lay having a forward and rearward range of movement, means to oscillate said lay, means to periodically change the range of movement of said lay from one range to the other, a weft replenishing mechanism positioned to cooperate with said lay in its rearward range of movement only, and means to shift said lay to its 85 90 forward range of movement at intervals of even numbers of beats of the lay.

In testimony whereof I have hereunto affixed my signature.

WILLIAM W. ROBERTSON.
